UNITED STATES PATENT OFFICE.

SAMUEL OLSON, OF CHICAGO, ILLINOIS.

STORE-SERVICE CONVEYER SYSTEM.

1,142,453.

Specification of Letters Patent. Patented June 8, 1915.

Application filed March 2, 1914. Serial No. 821,862.

To all whom it may concern:

Be it known that I, SAMUEL OLSON, a citizen of the United States, residing at Chicago, in the county of Cook and State of Illinois, have invented new and useful Improvements in Store-Service Conveyer Systems, of which the following is a specification, reference being had to the accompanying drawings, forming a part thereof.

This invention relates to conveying apparatus particularly designed for handling merchandise in stores or warehouses and it is, therefore, described in its relation to such use although its utility is not necessarily limited to this class of service.

The invention consists in the features and combinations of the elements described and shown in the drawings as indicated by the claims.

In the drawings:—Figure 1 is a side elevation of a conveyer system embodying this invention. Fig. 2 is a detail section on a larger scale taken as indicated at line 2—2 on Fig. 1. Fig. 3 is a detail section taken as indicated at line 3—3 on Fig. 2.

The conveyer system shown in the drawings comprises two continuously traveling belts, A and B, respectively, the former being mounted for vertical travel and the latter being guided to pass horizontally beneath the vertical conveyer. The belts, A and B, may be very satisfactorily constructed of a thick cotton fabric forming a webbing two or three feet in width. The vertically traveling belt, A, has fixed to it at intervals buckets, C, preferably composed of sheet metal and hinged to the belt at C¹. Each bucket consists of a bottom which is bent upwardly at C², to form

with the belt, A, a trough closed at each end by the flat side walls, C³, of the bucket. When this conveyer is installed in a store the several articles composing a single purchase and enumerated on a bill or memorandum will be deposited in one of the buckets, C, with such bill and lowered thereby to the inspecting and shipping department. As the bucket, C, passes around the foot wheel, D, of the vertical conveyer it will discharge its contents onto the slowly traveling belt, B, and the contents of each bucket, C, being thus discharged in a group on the belt or apron, B, can be readily checked up with the accompanying memorandum by an inspector stationed at the side of said traveling belt, B. To insure a

compact arrangement of the articles discharged from the buckets, C, there is provided a shield or guard, E, curved to conform approximately to the path of the bucket as it rounds the foot wheel, D, and serving to retain the articles in the bucket and gradually assume the support of said articles until the hinge, C¹, starts on its upward travel and the bucket is thus withdrawn from under its load. The group of articles thus deposited on the apron, B, will be slowly carried past the inspector and if found in satisfactory condition may be delivered by the same conveyer, B, to the wrapping department where they will be removed from the apron and prepared for shipment. The conveyer, B, may be of the very simplest construction as it is merely a traveling table or support for the articles; if desired it may be reinforced by auxiliary supporting rollers, B¹, disposed at intervals throughout its length.

As the bucket, C, of the vertical conveyer passes around the foot wheel, D, and proceeds upward it will depend from its supporting hinge, C¹, as indicated in Fig. 1, the slots, C⁴, in the side walls, C³, permitting the bucket to swing inwardly toward the belt so as to occupy less space than when extended in carrying position, thus reducing the necessary size of the containing shaft. In addition to reducing the necessary size of the shaft for the vertical conveyer the collapsible nature of the buckets increases the safety of operation, for the arm or head of a person momentarily extended inside of the shaft will not be seriously injured by contact with a descending bucket, since the bucket will readily fold upward leaving a clearance space in the shaft, and similarly if the rate of travel of the conveyer, B, should be such that the buckets, C, in rounding the foot wheel, D, might collide with previously deposited material on the belt, B, said buckets would simply yield by swinging about their hinges and would have no tendency to forcibly dislodge such material from its position on the horizontal apron.

It will be understood that as the bucket passes over the head wheel, F, it will resume its extended position in which it is supported by the engagement of a rod, G, with the ends of the slots, C⁴. The rod, G, is carried in hangers, G¹, secured rigidly to the belt, A, said hangers being slotted to permit a certain amount of play of the rod,

G, in the direction of travel of the belt, such play being required in order that the belt may conform to the arc of the head or foot wheel as the bucket passes around either of 5 said wheels.

Preferably, in order to maintain a fairly accurate time relation between the rates of travel of the two conveyers they should be operatively connected together as by the belt 10 indicated at H, and when it is found more convenient to apply the power at the head of the vertical conveyer, A, as by the belt, J, a take-up device, K, will be provided for the foot wheel, D, to keep both sides of the belt, 15 A, fairly tight. To keep the belt, A, properly centered on the head and foot wheels, D and F, the side walls, C⁵, of the buckets may extend back of the plane of the belt so as to act as flanges on the belt as the buckets 20 pass around said wheels; and these extending flanges of the bucket walls will preferably be formed with slightly flared projections, C⁶, to insure their proper engagement with the ends of the wheels, D and F, when 25 necessary.

I claim:—

1. In combination, a downwardly traveling belt, guiding means at the lower limit of its travel about which the belt passes 30 horizontally, load-supporting means extending from said belt transversely of the direction of travel both during the downward movement and also during the horizontal travel, whereby the load is gravitationally 35 discharged, and a horizontally traveling conveyer disposed below said guiding means in position to receive the load discharged.

2. In combination, a conveyer comprising a downwardly traveling belt, a foot wheel 40 around which said belt passes, a load support connected to the belt at two places separated longitudinally of the latter, whereby said support is caused to extend transversely from said belt both during its 45 downward travel and while rounding the said foot wheel, and a horizontally traveling conveyer disposed under the foot wheel.

3. In combination, a conveyer comprising a downwardly traveling belt, load-supporting means extending therefrom transversely of the direction of travel, guiding means at the lower limit of such travel about which the belt passes horizontally for discharging its load, a horizontally traveling 50 conveyer disposed below said guiding means in position to receive the load thus discharged, and a fixed guard which extends proximate to the path of said load-supporting means as the belt passes the said guiding means at its lower limit of travel, said guard serving to prevent premature discharge of the load.

4. In combination, a conveyer comprising a downwardly traveling belt, load-supporting 55 means extending therefrom transversely

of the direction of travel, guiding means at the lower limit of such travel about which the belt passes horizontally for discharging its load, a horizontally traveling conveyer disposed below said guiding means in position 70 to receive the load thus discharged, and a fixed guard which extends proximate to the path of said load-supporting means as the belt passes the said guiding means at its lower limit of travel, said guard serving to 75 prevent premature discharge of the load and terminating in a sloping portion directed toward the horizontal conveyer.

5. In combination, a conveyer comprising a head wheel, a foot wheel, a continuous belt 80 carried thereon, a horizontally traveling conveyer disposed below the foot wheel, a load support extending transversely from the said belt at its descending ply for conveying a load downwardly and discharging it onto 85 said horizontal conveyer, said load support being hinged to the belt and thus adapted to yield by folding of its supporting surface toward said belt to diminish its extent transversely therefrom.

6. In combination, a conveyer comprising a downwardly traveling belt, load-supporting means extending transversely therefrom at intervals in the length of said belt, guiding means at the lower limit of travel about 90 which the belt passes horizontally for discharging the loads from said supporting means, a horizontally traveling conveyer disposed below said guiding means in position to receive the loads thus discharged, and 100 operative connections between said conveyers for timing them with respect to each other to control the spacing of the loads deposited on the horizontal conveyer.

7. A vertical conveyer comprising a belt, 105 an upwardly open bucket extending transversely from the descending ply thereof, the bottom of said bucket being hinged to the belt and the side walls thereof being positioned beyond the edges of said belt whereby the bucket is adapted to collapse by folding of its load-supporting surface toward the belt, and means for limiting such swing of the bucket upon its hinge.

8. In a vertical conveyer, comprising a 115 belt and an upwardly open bucket extending transversely from the descending ply thereof, the bottom of said bucket being hinged to the belt, and its side walls being positioned beyond the edges of said belt to permit 120 collapse of the bucket by folding of its bottom toward the belt, a rod, and means by which it is secured to the belt with a limited amount of play longitudinally thereof, the side walls of the buckets having 125 curved slots engaging said rod for limiting the swing of the bucket toward and from the belt.

9. In a conveyer, comprising a head wheel, 130 a foot wheel and a belt mounted for travel

thereon, buckets disposed at intervals along said belt and each comprising a bottom extending transversely from the belt, and side walls positioned beyond the edges of 5 the belt and extending back of its plane to serve as flanges for centering the belt on said wheels.

10. In a conveyer, comprising a head wheel, a foot wheel and a belt mounted for 10 travel thereon, buckets disposed at intervals along said belt and each comprising a bottom extending transversely from the belt, and side walls positioned beyond the edges

of the belt and extending back of its plane to serve as flanges for centering the belt on 15 said wheels, the leading corners of said flanges being flared away from the belt edges to insure proper engagement with said wheels.

In testimony whereof I have hereunto set 20 my hand at Chicago, Illinois, this 26th day of February, 1914.

SAMUEL OLSON.
